UNITED STATES PATENT OFFICE.

WILMER S. SNOW, OF CHICAGO, ILLINOIS, ASSIGNOR TO NATIONAL X-RAY REFLECTOR CO., OF CHICAGO, ILLINOIS, A CORPORATION OF ILLINOIS.

DESIGN FOR A LIGHTING-FIXTURE.

51,188.

Specification for Design.

Patented Aug. 21, 1917.

Application filed June 20, 1917. Serial No. 175,827. Term of patent 7 years.

To all whom it may concern:

Be it known that I, WILMER S. SNOW, a citizen of the United States, residing at Chicago, in the county of Cook and State of Illinois, have invented a new, original, and ornamental Design for a Lighting-Fixture, of which the following is a specification, reference being had to the accompanying drawing, forming part thereof.

The figure is a side elevation of a lighting fixture, showing my new design.

I claim:

The ornamental design for a lighting fixture, as shown.

WILMER S. SNOW.
